UNITED STATES PATENT OFFICE.

ELZA E. WIFORD, OF SIDNEY, OHIO.

AUTOMATIC STOP FOR PHONOGRAHS.

Application filed May 20, 1922. Serial No. 562,406.

To all whom it may concern:

Be it known that I, ELZA E. WIFORD, a citizen of the United States, residing at Sidney, in the county of Shelby and State of Ohio, have invented certain new and useful Improvements in Automatic Stops for Phonographs; and I do hereby declare the following to be a full, clear, and exact description of the invention, such as will enable others skilled in the art to which it appertains to make and use the same.

This invention relates to automatic stops or brake mechanisms for phonographs or similar instruments.

An object of the present invention is to provide an improved simplified automatic stop of the character indicated. A further object is to provide a device of the character indicated embodying a novel, improved control device. A further object of the present invention is to provide a device of the character indicated in a compact, easily assembled form. Further objects will appear in the course of the following detailed description.

The invention consists in the novel construction, arrangement and combinations of parts as hereinafter more particularly described and claimed.

Two sheets of drawings accompany this specification as part thereof, in which like reference characters indicate similar parts throughout.

Figure 1 is a plan view of the top of a phonograph, parts being broken away to show the automatic stop device, the device being shown with the brake in locking engagement with the flange of the rotary disc;

Fig. 2 is a top plan view similar to Fig. 1, the device being illustrated in an intermediate position, the brake being out of engagement with the flange of the rotary disc but in position to be automatically released;

Fig. 3 is a plan view similar to the preceding figures, showing the brake released and in locking engagement with the flange of the rotary disc, and

Fig. 4 is a fragmentary vertical section taken on the line 4-4 of Fig. 1.

The present invention is particularly adapted for application to phonographs embodying, as illustrated in the drawings, a base A upon which is pivotally mounted a swinging sound conductor arm B carrying

a reproducer C and a stylus D. The arm B will be hereinafter referred to as the moving part. A suitable motor, not shown, is provided to rotate a vertical shaft F, carrying a disc E having a downwardly turned flange 37, the disc E being adapted to receive a sound record R having a spirally arranged sound groove S extending from adjacent the circumference to a circular groove adjacent the center. The structure thus briefly outlined is well known and in common use in instruments of this character.

The object of the present invention is to provide an automatic braking device to control the rotation of shaft F relatively to the movement of the moving part B so that when the stylus D, which is in engagement with the groove S of record R has been moved transversely of the record to the inner circular groove, a brake will be automatically released to stop the rotation of the shaft F and hence the record R.

A further object is to provide in connection with such an automatic stop, means for controlling the automatic device so that in the preliminary movement of setting the stylus D in the outer grooves at the commencement of the operation, the moving arm B may be freely moved backwards and forwards to a limited degree without releasing the brake mechanism and which will also permits the maintenance of the braking mechanism in operative or set position during this preliminary stage and after the machine is set in operation irrespective of the speed of rotation of the record which is lower than normal during the first stages.

To accomplish these objects, I provide an auxiliary base plate 1 adapted to be secured to the top of the phonograph by screws 2, and under the rotary disc E, as is illustrated. Mounted on plate 1 are spaced pivot carrying brackets 3 to which is mounted a shaft 4 carrying a gear 5 adapted to mesh with a worm gear 6 carried by shaft F and also carrying a screw gear 7 adapted to engage teeth 8 of a rotary friction disc 9. A complementary friction disc 10 is pivotally mounted over and in contact with friction disc 9 and above the complementary friction disc 10 is rotatably mounted a brake member 15 provided with a catch notch 16 and carrying a brake shoe 24 adapted to engage flange 37 of disc E to brake the

same. Over brake member 15 is pivotally mounted a lever 11 having a short arm 12, said lever 11 being pivotally connected as by a link 13 to moving part B as by a pivot 14. Brake member 15 is connected with lever arm 11 by means of a spring 26 tending to normally draw brake shoe 24 into engagement with flange 37. The frictional discs 9 and 10 together with brake member 15 and lever 11 are mounted on a common pivot shown as screw 30.

Upon the complementary friction disc 10 a catch member 18 having a hook 17 adapted to engage catch notch 16 of brake 15 is pivotally mounted as at 19 and connected as by a pivot 20 to the short arm 12 of lever 11. Intermediate pivots 19 and 20 a short transverse slot 21 is provided in the short arm 12 to receive a pin 22 carried by catch member 18 and adapted to limit the motion of catch 18 relative to pivots 19 and 20.

Adjacent the circumference of frictional members 9 and 10 and also adjacent catch 18 is pivotally mounted a control member 31 pivoted to plate 1 as by a screw 32. This control member 31 carries a pin 35 adapted to play within a notch 34 cut in the periphery of a guide washer 33 to control and limit the stroke of the control member 31. A spring 36 is provided tending to normally press control member 31 against catch 18 as illustrated in Fig. 1. The slot 34 in washer 35 is so adjusted, however, as to prevent control member 31 from engaging brake member 15 even in its most extreme downward position as illustrated in Fig. 2.

In operation, the moving part B is moved to its extreme outermost position, as illustrated in Fig. 1, rotating lever 11 by means of link 13 and through lever 11 and arm 12, rotating frictional plate 10, together with catch 18 and through catch 18 the brake member 15, all into the positions illustrated in Fig. 1, showing the brake shoe 24 in locking engagement with the flange 37 of rotary disc E. The position thus illustrated and described shows the automatic brake device set and the brake in operative position. Upon movement of the moving part B toward the circumference of the disc, in order to place the stylus D in the outermost grooves of the record, it will be apparent that lever 11 will be rotated in a counter clockwise direction at the same time rotating friction disc 10 through the connections of lever arm 12 and catch 18 and pulling brake member 15 by means of hook 17 in engagement with notch 16 until the brake shoe 24 is withdrawn from contact with the flange 37, thus permitting the rotary shaft F to revolve with the rotary disc E. The rotation of shaft F will, through counter shaft 4, rotate friction disc 9 also in a counter clockwise direction and at the same or a lower speed than friction

disc 10, which will continue to be rotated through the feeding in of stylus D toward the center of record R by means of the spiral sound groove S.

When the stylus D has reached the central circular groove of the record its transverse movement over the record ceases and hence the movement of lever 11. Friction gear 10 will however, continue to advance in a counter clockwise direction by reason of its frictional contact with the friction disc 9 operated by rotary part F. This continued movement of friction disc 10 will advance pivot 19 of catch 18 relative to pivot 20, thus withdrawing hook 17 from notch 16 of brake member 15 and releasing brake member 15 which under the tension of spring 26, will rebound into locking engagement with flange 37 of the disc E, thus stopping the rotation of said disc and the motor, as illustrated in Fig. 3.

In association with the operation thus described, it will be noted that in the initial position of the apparatus as illustrated in Fig. 1, the control member 31 is in engagement with the catch 17, tending to hold said catch in locking engagement with the brake member 15 regardless of the relative tensions on pivots 19 and 20 as they may be effected by the movement of moving arm B which may be moved backwards and forwards without releasing the catch. So also the relative speed of moving part B and record R is immaterial so long as control member 31 thus engages catch 18. As this control member, however, is so adjusted with relation to pin 35 and notch 34 that it cannot contact with brake member 15, it will be obvious that as the moving part B advances over the record into the position illustrated in Fig. 2, catch 18 passes from engagement with control member 31 and thereafter any modification of the tension on pivots 19 and 20 will operate to release the brake as previously described.

Various modifications and arrangements of the elements above described will readily suggest themselves to those skilled in the art, but all within the scope of the present invention.

Having thus fully described my invention, I claim:

1. An automatic stop for phonographs and the like having a rotary part, a moving part and a brake, comprising a member rotated from the rotary part, a complementary member rotated by the moving part, a catch member to control the brake carried by the complementary member and means operated by the moving part to rotate said complementary member and to effect the catch.
2. An automatic stop for phonographs and the like having a rotary part, a moving part and a brake, comprising a member rotated from the rotary part, a complementary

member adapted to be rotated by the moving part, a catch controlling the brake pivoted on said last mentioned member, the breaking of which toggle will operate to release the brake.

3. An automatic stop for phonographs and the like having a rotary part and a moving part, comprising a base, a part operated from the rotary part, a complementary part adapted to be operated from the moving part, a brake member and a lever connected with the moving part, said parts, brake member and lever being all concentrically mounted on the frame, spring means connecting the brake member and lever tending to throw the brake member into locking position; and a catch member controlling the brake pivoted to the complementary part and to the lever forming a toggle therewith through which the last mentioned member may be rotated and by the breaking of which toggle the catch is withdrawn from engagement with the brake member.

4. An automatic stop as described in claim 1, in combination with independent means for retaining the catch in engagement with the brake member during a predetermined part of the movement of the moving part.

5. An automatic stop as described in claim 1, in combination with a tension member operating on the catch member during a predetermined part of the movement of the moving member to retain the catch in engagement with the brake irrespective of the

movement or the non-movement of the moving part.

6. An automatic stop as described in claim 1, in combination with a pivoted member, spring means operative of the pivoted member, and stop means limiting the rotation of the pivoted member, said pivoted member adapted to engage the catch member to control it independently of the moving part during a predetermined period of the latter motion.

7. An automatic stop for phonographs and the like having a rotary part and a moving part, comprising a base, a part operated from the rotary part, a complementary part adapted to be rotated from the moving part, a brake member and a lever connected with the moving part, said parts, brake member and lever being all concentrically mounted on the frame, spring means connecting the brake member and the lever tending to throw the brake into locking position, a catch controlling the brake member pivoted to the complementary part, and to the lever forming a toggle therewith and a control member pivoted to the frame adjacent the catch, spring means to throw the control member against the catch member to retain the latter in engagement with the brake member and stop means for limiting the throw of said control member, substantially as specified.

In testimony whereof I affix my signature.
ELZA E. WIFORD.
